UNITED STATES PATENT OFFICE.

FRANK O. WOODLAND, OF WORCESTER, MASSACHUSETTS.

BAND-AFFIXING MECHANISM.

1,151,504.

Specification of Letters Patent. Patented Aug. 24, 1915.

Application filed June 13, 1913. Serial No. 773,488.

To all whom it may concern:

Be it known that I, FRANK O. WOODLAND, a citizen of the United States, residing at Worcester, in the county of Worcester and State of Massachusetts, have invented a new and useful Improvement in Band-Affixing Mechanism, of which the following is a specification, reference being made therein to the accompanying drawings.

10 This invention relates to mechanism for affixing bands, or encircling labels, to articles whereon the band or label extends completely around the circumference, and has its ends lapped over each other for some 15 distance and adhesively secured together; the invention being more especially designed for employment in mechanism for banding cigars or the like; but it is also applicable to machines for banding or labeling other 20 and various kinds of articles.

The prime object of my present invention is to provide, in conjunction with an undertuck lapper, or element which lays the first end of the band or label, of means for preventing any recoil, escape, or buckling of the band when said undertucking lapper commences its retractive movement, and until said first laid end is caught by the overlying opposite end of the band; the retainer 25 means then retreating with the undertuck-lapper element, while the overlying end of the band is laid in position.

Another object is to provide a lapper with a yieldable or differentially moving device 30 that temporarily retains a hold upon the first placed half of the band or label, after the lapper-blade or wiper member has commenced to back off to allow the overclosing lapper or opposite wiper member to smooth 35 down the gummed end of the band upon the first laid end.

Another object is to provide a lapper or wiping-on device having a slot or recess at or near the end of its working face, and 40 provided with a movable contact-member arranged within said slot for affording a dual contact and pressure upon the band, and means for producing a yieldable and 45 resilient action, tending to normally press 50 said contact-member toward the end of the lapper, but permitting said member to be moved backward within the slot, as more fully hereinafter explained.

For attaining these and other objects, my 55 invention consists in mechanism the nature, construction and mode of operation of

which is set forth in the following detailed description, and illustrated in the accompanying drawings; the particular subject matter claimed being definitely expressed in 60 the summary.

In the drawings, Figure 1 represents a diagrammatic elevation view of such parts of a band-affixing mechanism as will show the nature of my invention. Figs. 2 and 3 65 are comparative views of the oscillating lapper devices illustrating the action of my invention. Fig. 4 is a central sectional view showing a preferred form of embodiment of this invention. Fig. 5 is a view of the 70 face of the improved lapper appliance, and Fig. 6 is a view of the back of the same. Fig. 7 is a sectional view, and Fig. 8 a 75 back view showing a lapper and modified form of the supplemental retaining member. Figs. 9 and 10 represent a side and back view showing another modification. Figs. 11 and 12 show a side and back view 80 of a further modification in the construction.

The improved lapper appliance, which constitutes the subject of my present invention, is designed for use in banding machines of the class set forth and described in my previous application for Letters Patent, Serial No. 585,619, and in machines of similar character, wherein the band or long labels are required to be passed completely around the articles to which they are applied; the band being of greater length than 90 the circumference of the article, or the part thereof, about which it is applied.

For a full understanding of the banding machine in detail, resource may be had to said prior application for patent; but for the purposes of the present application, which relates to the improvement of the lappers or band-laying means only, it is deemed sufficient to state that the lappers are arranged to move from a primary position above the work (see Fig. 1) down to the band, which latter is delivered across the cigar or article. The lappers then have imparted to them, respectively, a right and left oscillating movement about the central axis of the cigar, as indicated by the dotted lines in Figs. 2 and 3; the extent of the oscillative movement being more or less as may be required for lapping the ends of the band past each other to a greater or less 100 degree.

Referring to the drawings, the part

marked B represents a band-supply holder, only a portion of which is here shown.

G indicates the glue or gum-applying roll or device by which the bands are glued or gummed at or near one end and taken from the supply holder, one at a time, and delivered across the cigar C, article to be banded, as indicated at 3 on Fig. 1; the cigar being meanwhile supported upon a suitable rest 4 that sustains the same with its longitudinal axis approximately in central alignment with the axis about which the lapper-carriers oscillate when in the operation of affixing the band or label thereto.

15 5 indicates the grip member for centrally holding the band.

The means for moving the lapper carrier arms may be the same as described in my prior application for Letters Patent, or any 20 other approved means whereby an oscillatory movement of the lappers, or wiping on devices of the character described, is effected.

The numerals 40 and 41 indicate the oppositely oscillating lappers, and 42 and 43 the carrier-arms or levers upon which said lappers are mounted.

In accordance with my present invention I provide, in combination with the lapper or device 40 which wipes on the first laid end of the band or label 3, and which I herein term the undertuck lapper, a supplemental means for giving pressure or contact against the surface of the band, and adapted 35 for retaining its contact position after the lapper proper starts on its retractive movement. In the preferred embodiment of this invention the undertuck lapper is formed with a slot 6 at or near its outer end, and 40 is furnished with a movable tongue, presser-finger or swinging-contact-member 10, connected therewith in a manner to project at the face of the lapper blade, and to be yieldably movable within said slot; the end of 45 said tongue or supplemental member being adapted for contact with the end portion of the band or label as the lapper wipes it around the cigar; and for retaining its pressure against the band for an interval of 50 time after the lapper commences its backward movement, as may be observed by a comparison of the positions shown in Figs. 2 and 3, thereby preventing the end from any backward release.

55 As shown in the drawings, Figs. 1 to 6, the tongue or presser-finger 10 is made as a telescoping stud or puppet comprising two shells 7 and 9, having an expanding spring 8 inclosed within the interior thereof. 60 (See section, Fig. 4.) One end of the tongue extends through the slot 6 and its other end is hingedly connected at 12 to an ear or projection 13 formed upon or attached to the back of the lapper 40. The sides of 65 the shell 7 are provided with shoulders 14

that limit the extent to which the tongue can protrude from the slot.

The overclosing lapper 41 is, as heretofore, made practically plain, but with an outwardly inclined end adapted to slide over the first end of the band with ease and facility. Said lapper is timed to act a little subsequent to the action of the lapper 40, so that the ends of the band can pass each other without conflicting. 75

Figs. 7 and 8 show a modification wherein the retainer or supplemental contact member 10^a is constructed as a bend or loop formed upon the end of a spring wire 10^a having its rear end secured to the lapper carrier arm 42, the loop projecting through the slot 6 and being movable therein by the yield and resilience of the extended portion of the wire. 80

Figs. 9 and 10 illustrate a modification 85 wherein the retainer or contact member 10^b is made as a tongue hingedly connected to a swinging arm 15 that is pivoted to swing upon the journal or cylindrical end of the lapper-carrier 42 upon which the lapper itself is mounted; the head of the lapper being slotted at 16 to receive and support said swinging arm 15. A pull spring 18, connected across from the shank of the tongue to the back of the lapper, acts for giving a normal forward pressure at the end of the tongue that protrudes from the slot. A pin or lug 17 is provided for limiting the forward swing of the tongue. The end of the tongue can move longitudinally 90 in the slot by the swing movement of its pivoted arm 15. 100

In the modification shown by Figs. 11 and 12 the retainer tongue or contact member 10^c is hinged to the lower end of a flat 105 spring 20 that has its upper end rigidly attached by a screw 21, or equivalent fastening, to the back of the lapper body 40; the tongue 10^c projects through the slot 6 and swings freely on its hinge. A pin or lug 17 110 limits the extent of its projection.

In each of these forms of embodiment the effective operation is substantially the same; the operation being as follows: When the undertuck lapper 40 wipes the first end of the band or label 3 and passes beneath the cigar C, the end of the tongue or member 10 moves with the lapper and contacts with the band, but by friction or pressure thereon is forced toward the rear end of the slot 6, 115 assumes a position in relation to the lapper face and band approximately as shown in Fig. 2. Then when the undertuck movement has reached its limit and the lapper 40 starts on its retractive movement, the end of the tongue or member 10 remains at its given position against the band for an interval corresponding to the length of the slot 6, while the end of the lapper moves 120 backward, thereby retaining the end of the 125 band. 130

band as placed and preventing it from escaping, buckling or being drawn back by friction of the lapper against its surface, and until the over-closing lapper 41 has 5 brought the end portion 2 of the band 3 far enough over to catch upon the end 1 and confine the same against further liability of its displacement or backward release, or until the parts assume a position approximately as illustrated in Fig. 3, when there 10 is no further necessity of retaining the end 1, since the glued portion of the end 2 is immediately closed over the end 1 by the overclosing lapper 41 and the undertucking lapper with its supplemental retainer or 15 contact member swings back to primary position.

This invention is an important advance in the art, inasmuch as the retainer means, by 20 affording a dual and differential hold upon the under-lying end of the band or label, insures the more perfect and close affixment of bands, and a greater uniformity in execution; while it facilitates the successful 25 rapid operation of the banding machine.

I am aware that in practising my invention, changes in the detail of embodiment may be made by persons skilled in the art without departure from the nature and scope 30 of the invention as expressed in the claims. I do not, therefore, wish to be limited to the special forms and details as shown. But

What I claim and desire to secure by Letters Patent, is—

35 1. In a banding machine, comprising means for supporting the cigar or article to be banded, means for presenting a band or label, and means including an undertuck lapper and an over-closing lapper for lap- 40 ping the opposite ends of the band or label upon each other; and a yieldable presser member carried in conjunction with the undertuck-lapper and acting near its fore-end for pressing against the band, said presser 45 member having a limited extent of lost motion in respect to the lapper movement, substantially as set forth.

2. In mechanism for affixing bands to 50 cigars or the like, comprising means for gumming one end of a band and presenting it across the cigar, a grip-device for retaining the central portion of the band in place, and oscillating undertuck and overclosing lappers that clasp the ends of the band to 55 gether, and a supplementary member coacting with the under-tuck lapper and adapted for temporarily retaining the first laid end of the band against the cigar as the under- 60 tuck lapper recedes before the over-closing lapper.

3. In mechanism for affixing bands to 65 cigars or the like, the combination with means for gumming and presenting a band adjacent to the cigar at position for affix- 70 ment; of means for lapping the ends of the

band about the cigar, including an under lapping element, a supplemental contact member associated with said under lapping element and adapted for preventing the band from breaking or slipping backward as 75 the under lapping element is being retracted.

4. A compound lapper element for band- 80 affixing machines, comprising a plurality of band-pressing members simultaneously operated, but having variable movements; one member adapted for retaining the end of the band for a limited time after the other member commences its reverse movement, and means for imparting an advancing and re- tractive action to said lapper.

5. In a banding machine, an under-tuck lapper means comprising two combined members severally adapted for contact with the band, and capable of limited differential movement at their contacting faces, and 85 mechanism for operating said combined lapper means to carry the first laid end of a band about the surface of a cigar or the like.

6. In a banding machine, an under-tuck lapper comprising two unitedly acting band- 90 pressing members, one member of which is yieldably carried upon the other member and acts supplemental thereto affording a differentially releasing contact with the band; in combination with an over-closing 95 lapper that acts upon the opposite end of the band.

7. The combination with means including an under-tucking lapper and an overclosing lapper adapted for lapping or wiping a 100 band or label about a cigar or the like; of a movable supplemental retainer member mounted in connection with the undertucking lapper or wiper element, its end protruding at the face thereof and adapted for 105 contact with the band or label for temporarily retaining the end of the label in position while the wiper means starts on its re-tractive movement.

8. A lapper or wiper element for band- 110 affixing mechanisms, having a wiping face for wiping on a band or label; and provided with a yieldingly attached supplemental contact-member accompanying said face, whereby dual contact with the band is ef- fected, said means adapted for affording differently timed backward movements of the wiping face and contact member.

9. A lapper or wiper device for the pur- 115 pose specified, comprising a main body hav- ing a head adapted for pivotally mounting it upon a carrier, and a slot at or near its fore-end, a swinging tongue or contact-mem- 120 ber movable within said slot and protruding at the face of the lapper for contact with the bands, and a yieldable means for normally pressing the said tongue toward the outer end of the slot.

10. The combination, with means for gum- 125 ming and delivering bands or labels, and a 130

cigar supporting rest, of a pair of oppositely oscillating lapper devices, one of said lapper devices being provided with a slot in its working face, a retainer tongue or contact member arranged through said slot to protrude at the face of the lapper, and mounted to swing within the slot, and a spring acting to afford yielding resilience to said tongue,

and for normally carrying it toward the fore-end of the slot.

Witness my hand this eleventh day of June, 1913.

FRANK O. WOODLAND.
